UNITED STATES PATENT OFFICE.

WILLIAM CELEDA, OF NEWARK, NEW JERSEY.

SMOKING-PIPE.

1,401,876.

Specification of Letters Patent. Patented Dec. 27, 1921.

Application filed October 7, 1919. Serial No. 329,061.

To all whom it may concern:

Be it known that I, WILLIAM CELEDA, a citizen of Bohemia, having declared my intention to become a citizen of the United States, and a resident of Newark, in the county of Essex and State of New Jersey, have invented a new and improved Smoking-Pipe, of which the following is a description.

10 My invention relates to smoking pipes and particularly to a pipe having means to catch the nicotin and prevent the direct passage of the smoke from the bowl to the mouthpiece.

15 The general object of my invention is to provide a pipe of the indicated character improved in various particulars whereby to provide a nicotin chamber of ample proportion and so arranged relatively to the stem and mouthpiece as to insure the settling and deposit of the nicotin, and whereby also to prevent the passage of saliva to the bowl, as well as to cause the smoke to be cooled before passing through the mouthpiece.

20 25 More specifically, the invention has for an object to provide a structural embodiment of the invention reflecting practical considerations with respect to the possibility of thorough cleaning of the pipe and the convenience of assembling and disassembling the parts.

Reference is to be had to the accompanying drawings forming a part of this specification, it being understood that the drawings are merely illustrative of one example of the invention.

Figure 1 is a sectional side view of a smoking pipe embodying my invention, a portion of the bowl being broken away; 40 Fig. 2 is a fragmentary sectional elevation showing the valve for preventing entrance of saliva to the bowl in the rearward position as when the smoke is drawn into the mouthpiece;

45 Fig. 3 is a cross section on the line 3—3, Fig. 1;

Fig. 4 is a cross section on the line 4—4, Fig. 1;

50 Fig. 5 is a perspective view of a fitting employed between the mouthpiece and the adjacent stem section forming a cage for the valve;

Fig. 6 is a perspective view of an interior tubular element to be hereinafter referred to;

55 Fig. 7 is a perspective view of a device

to be associated with the valve in the preferred form of the invention;

Fig. 8 is a perspective view of the valve;

Fig. 9 is a view similar to Fig. 2 showing a construction from which the valve spring 60 is omitted.

In carrying out my invention in accordance with the illustrated example, the bowl 10 of suitable design is formed with an integral stem section 11 and secured to the same is a shell 12 extending adjacent to the mouthpiece 13, said shell being connected with the mouthpiece through a coupling or detachable stem section 14. The section 14 has a reduced front end externally threaded 70 as at 14^a to engage internal threads on the rear end of the shell 12 while said section 14 has internal threads at its rear end engaging external threads on the mouthpiece 13 as indicated at 14^b. On the section 14 at the front and within the shell forwardly extending parallel arms 15 are provided supporting at the front ends thereof a ring 16 having internal threads 16^a.

A tubular element 17 ranges lengthwise 80 within the shell 12 and spaced therefrom to provide an intermediate chamber 19, said element having a throughbore 18. The front end of the tube 17 extends into the reduced forward end 12^a of shell 12, said reduced 85 end being connected at its base with the body of the shell by a flange 12^b projecting radially inward from said body. At the flange 12^b a bushing 12^c of cork or the like may be provided in the flange 12^b and at the adjacent 90 base of the reduced end 12^a to make a tight joint about the tube 17. Said tube 17 has an annular flange or collar 17^a that bears against flange 12^b and limits the forward movement of the tube. Adjacent to the rear 95 end of tube 17, the same has external threads 17^c engaging in the threads 16^a, the extreme rear end 17^a beyond the threads 17^c being unthreaded.

A forwardly facing cup-shaped valve 20 100 is employed at the rear end of the tube 17 between the same and the mouthpiece 13 to prevent saliva passing to the pipe bowl through said tube. Said valve slidably fits over the unthreaded rear end 17^d of stem 17 105 and it may, as shown, have an annular flange 17^a for a fingerhold, said flange also constituting a deflector for smoke passing out of the bore 18. The sides of the valve 20 have holes 20^b therein for the outward 110

passage of the smoke into the chamber 19. Thus, in the act of drawing the smoke from the bowl through the stem and through the mouthpiece 13, the valve 20 will be drawn 5 rearwardly and any forward pressure exerted by the smoker will reseat the valve. In any case it is prevented from completely leaving the stem 17.

At the forward end of the mouthpiece 13 suitable means is provided, limiting the rearward movement of the valve, said means preferably including a forwardly projecting member or members 21. In the form shown in Fig. 9, the dimensions of the parts 15 are such that the valve 20 will directly contact with the stop member 21. In the form shown in Figs. 1 to 4, the valve is acted upon by a coiled spring 22 extending at its front end about the rearwardly projecting stem 20 on the valve and abutting the rear end of said valve. The rear end of the spring 22 is accommodated in and abuts against a housing 23 which in the illustrated form has lateral ears 23^a thereon adapted to rest against 25 an annular internal flange or stop 14^a of stem section 14, the back of said housing lying adjacent to the front end of the stop members 21. In the last described construction the spring tends to force the valve 20 to 30 a seat against the end of the tube 17 but the spring yields to the suction incident to drawing the smoke into the mouthpiece. The diameter of the ring 16 is less than the 35 interior diameter of the shell 12 so that nicotine and saliva may pass forwardly between said ring and said shell to the forward main portion of the chamber 19.

With the described construction it will be clear that smoke drawn rearwardly through 40 the stem section 11 and tube 17 is permitted to pass laterally through the openings 20^b of the valve 20 and will be laterally deflected by the flange 20^a thereby permitting the nicotine to be deposited in the chamber 45 19 and causing the same as it collects to move forward and downward into said chamber toward the front end thereof. The smoke freed from the nicotine may pass readily by the housing 23 or directly from the 50 neighborhood of the valve to the mouthpiece through the stop members 21 thereof, the arrangement being such that neither the valve nor the housing can close the passage leading rearwardly to the mouthpiece.

55 I would state in conclusion that while the illustrated example constitutes a practical embodiment of my invention, I do not limit myself strictly to the mechanical de-

tails herein illustrated, since manifestly the same can be considerably varied without departure from the spirit of the invention as defined in the appended claims. 60

Having thus described my invention, I claim:

1. A stem for smoking pipes including a 65 shell, a tube ranging longitudinally in said shell and spaced therefrom to form a chamber, a separate mouthpiece, means detachably connecting said mouthpiece with said shell, a valve slidably sleeved on the said 70 tube at the rear end, and stop means to limit the rearward movement of said valve, said stop means including stop members on the front end of the mouthpiece.

2. A stem for smoking pipes including a 75 shell adapted to fit the fixed stem section of a pipe bowl, a tube in said shell and spaced therefrom to form an intermediate chamber, the front end of said tube removably fitting the front end of said shell, a mouthpiece, a stem section, a coupling detachably securing said rear stem section to said shell, a cup valve sleeved on said tube at the rear end and adapted to vibrate forward and back on said tube to a forward position closing said tube or to a rearward position permitting the escape of smoke from the tube, and stop means to limit the rearward movement of the valve. 80

3. A stem for smoking pipes including a 90 shell having means at its front ends to secure it to the fixed stem section of a pipe bowl, a tubular element within said shell and tightly fitting the forward end thereof, a detachable coupling section on the outer 95 end of said shell, a mouthpiece detachably secured to said coupling section, said coupling section extending forwardly within the shell, said forwardly extending portion of the coupling section comprising separating arms, and a ring at the front end of said arm, thereby forming a smoke chamber within said arms and rearward of said ring, said chamber being in communication with said mouthpiece, said tubular element extending at its rear end through said ring and protruding into said chamber, and a valve slidable on the protruding end of said tubular element within said chamber, said valve having a lateral outlet for the escape 100 of smoke when the valve is in the rearward position, and a spring tending to maintain the valve in the forward position closing 105 said tubular element. 110

WILLIAM CELEDA.
